Claims priority, application Italy May 14, 1960

12 Claims. (Cl. 101—181)

The present invention relates to a method and apparatus for controlling the register on rotogravure printing machines.

It is known that the polychrome printing process consists in successively printing monochromatic images, thus obtaining a good polychrome image, provided that the various monochromatic images are applied in exactly superposed relationship.

In the particular case of rotogravure machines, the sheet is continuously unwound from a roll of paper, goes through a first section where the first monochromatic image is printed and subsequently passes through the following sections, where the other monochromatic images are printed in turn, and finally is wound up on a roll.

Various systems are known for effecting the automatic control of the printing register, that is the perfect superposing of the monochromatic images.

These existing systems usually work as follows:

The first section of the machine prints a register mark in addition to the corresponding monochromatic image, and the register mark is detected, in each of the following sections, by a photoelectric cell system that generates a signal indicating the position of the paper in that section; furthermore a device rigidly connected to the printing roll of each section generates a signal indicating the angular position of said roll; and finally a control device receives both signals and compares them, that is compares the relative position of the paper and of the printing roll of the related section, and, if necessary, corrects the position of the printing roll relative to the paper by means of a correcting motor and a mechanical differential.

Since the above arrangement is provided at each section of the printing press, this equipment is very complicated and consequently very expensive.

One of the purposes of the present invention is to provide an automatic control system which is much more simple and ensures satisfactory and safe operation.

In accordance with an important aspect of the invention, a single control group is provided that acts in cycle for checking and correcting in turn the working conditions in each section of the press.

Other purposes and characteristics of the invention will be apparent in the following description of an illustrative embodiment with reference to the attached drawings wherein on which

FIG. 1 is a diagrammatic view of an automatic control device of the above described existing type;

FIG. 2 is a diagrammatic view of a register control device according to the present invention;

FIG. 3 is a diagram of the disposition of the register marks provided on a sheet of the paper in accordance with this invention;

FIG. 4 is a diagram of a photoelectric detection device included in the apparatus embodying this invention;

FIG. 5 is a diagram of a magnetic detection device for indicating the roll position in the apparatus embodying this invention;

FIG. 6 is a diagram of the control device included in a preferred form of the apparatus embodying this invention;

FIG. 7 is a diagram illustrating the output voltage of the control device;

2

FIG. 8 is a diagram of a circuit which operates the correcting device;

FIG. 9 is a diagram of a circuit for operating the selector;

FIG. 10 is a diagram of the voltage at various points in the circuit of FIG. 9;

FIG. 11 is a diagram of the selector;

FIG. 12 is a diagram of the voltage at various points in the selector of FIG. 11;

FIG. 13 shows the disposition of the register marks according to another embodiment of the invention, and

FIG. 14 is a diagram of the voltage at a number of points in the circuit.

As clearly shown on FIG. 1 of the drawing, a device of the known type includes a roll B_1 from which a continuous sheet of paper 1 is unwound and then undergoes the action of the printing rolls S_1, S_2 etc. in the subsequent sections before being rewound on a roll B_2 .

The several rolls S_1, S_2 , etc. are driven by the main drive MP of the printing machine with roll S_1 of the first section being driven directly, while for each of the remaining sections, the drive is effected through a differential D_2 , adjusted by a correction motor M_2 , under the action of a control device C_2 .

A photoelectric detector TE_2 is located in front of the sheet coming out of roll S_2 , while a magnetic detector TM_2 turns as a unit with the printing roll S_2 ; the signals generated by the two detectors TE_2 and TM_2 being transmitted to the C_2 device that compares them and, if necessary, operates motor M_2 and consequently corrects the rotational position of roll S_2 , through differential D_2 .

According to the known procedure, the controlling group C_2, TE_2, TM_2, M_2 , must be repeated for each of the printing sections with the exception of the first section.

According to the present invention, a more simple and efficient automatic control system is obtained, which represents a big saving in equipment as only one photoelectric head serves to detect all of the register marks, and only one magnetic head detects the position of one of the various printing rolls and finally only one device compares the relative phases of the signals obtained from the two detectors and operates the correction means associated with each of the printing rolls, excepting the one with which the magnetic detecting head is associated.

The diagram on FIG. 2 illustrates the above arrangement embodying the invention. In this diagram only four printing rolls have been shown for the purpose of simplification, but it is to be understood that a greater number of sections may be included.

There is only one controlling system TE, TM, C and it is equipped with an automatic selector S , operated electronically. The operation will be made clear with the following:

For example, in a machine for the printing of six colors, each roll of the first five sections, prints, in addition to the corresponding monochromatic image, a register mark near the edge of the sheet. At the start-up, the machine is checked manually, that is the various monochromatic images are checked to see whether they are printed in exactly superposed relationship. Then sheet 1 appears as shown on FIGURE 3, where numerals 2 and 3 identify the lines defining the size of the sheet, that is the lines along which the paper will be cut, after printing, and numeral 4 identifies polychrome printed area.

On the edge of the sheet five register marks, $I_c, II_c, III_c, IV_c, V_c$, are shown each of them being in the position where it is printed when the machine is in correct register and the polychrome image is perfect.

After the machine has been manually checked, magnetic recorder device TM and photoelectric detector TE are inter-connected in such a way that, when marks $I_c, II_c, III_c, IV_c, V_c$ pass in front of head TE , a corre-

sponding signal is recorded in the magnetic memory of device TM.

At this point the preparatory stage ends and automatic operation may commence.

The machine, driven by main drive MP, acts on the sheet 1 to advance the latter past the rolls S₁, S₂ . . . S₆ which respectively print thereon images in the corresponding colors together with the respective register marks I_c, II_c . . . V_c.

Upon commencing automatic operation, the selector S is in position 1. The first mark on each portion of sheet is detected by device TE and a resulting signal is compared by device C with a signal resulting from the first mark recorded in the magnetic memory. If the detected and recorded marks are simultaneous, it means that the first monochromatic image that has been printed is, in relation to the last one, in the same relative position it had at the beginning, when the machine was checked with the desired precision. The control device C compares the occurrence of the two marks, and, when both marks are simultaneous, does not transmit any driving action to motor M₁.

If, on the contrary, the two signals are not simultaneous, device C detects the need for a correction and, through selector S, which—as mentioned above—is in its first position, acts on motor M₁, rotating it in one direction or the other; this rotation of correction motor M₁ acts, through differential D₁, on printing roll S₁, to restore the latter to its correct relative position. Immediately after the first signal has passed, to motor M₁, the selector S advances automatically to position 2.

The unit is then ready to effect in a similar way the comparison of the second register mark II_c and the corresponding second magnetic signal: as described above, with the only difference that any possible correction required acts on roll S₂, because of the position of selector S.

It is superfluous to repeat the same description for all the remaining printing sections.

In short, the device according to the invention, during the operation of the machine checks, for each sheet into which the web will be cut, whether the first five monochromatic images printed by the first five machine sections have the same positions relative to the printing roll of the last section as they had at the beginning of operations, that is, after the manual checking of the machine and, if necessary, suitably corrects the position of each of the rolls.

The electrical circuits capable of functioning as described above can have different forms, of which illustrative examples are described below:

(a) Detector TE

As shown on FIG. 4, the detector TE includes a light system, formed by a lamp L and a lens O₁, that concentrates the light of the lamp, generating a luminous spot on the sheet 1, in the position of marks I_c, II_c . . . IV_c and a photoelectric cell E, which receives from another lens O₂ the light coming from said sheet 1, that is which senses the above mentioned marks, as the latter pass the detector.

The signal generated by the photoelectric cell is sent to an electronic amplifier, which includes tubes 5, 6, 7.

Voltage variations occur at the points 8, 9, 10 of the amplifier circuit, as diagrammatically illustrated.

(b) Detector TM

As shown on FIG. 5, the detector TM includes a magnetic drum, 11, that is a pulley with a band of magnetic material thereon capable of receiving a magnetic recording, a magnetic head 12 and an amplifier with three tubes 13, 14, 15 and with an output 16.

The magnetic head 12 has three functions, namely:

(I) It cancels the previous recording on the magnetic drum, and for this purpose the coil of the magnetic head is connected to a source of continuous voltage.

(II) It records on the magnetic drum, and for this purpose the coil of the head 12 is connected between points 17 and 18 of the circuit for the detector TE (FIG. 4); and

(III) It detects the signals recorded on the drum, and for this purpose the coil of the head is connected to the amplifier of FIG. 5 and, more precisely, to the grid circuit of valve 13.

The amplitude of the signal generated by the head TM in response to a recorded magnetic impulse on the magnetic drum is a function of the drum's speed, and this fact constitutes a source of error.

To avoid that cause of error, a signal is introduced at the entrance of valve 14, from a tachometric dynamo, not shown, the speed of which is proportional to the speed of the main drive MP (FIG. 2).

(c) Detector Device C

As shown in FIG. 6, the circuit of the control device C is formed by a channel that elaborates the signal from detector TE and a channel that elaborates the information from recorder TM. Each channel includes a squaring circuit (part 43) a bistable circuit (part 44) and an integrator circuit (part 45). The signals from the apparatus TM consist of negative voltage impulses (FIG. 14a) which surge whenever the areas of the band on which magnetic impulses have been recorded pass under the magnetic head.

Such voltage impulses indicate the position of the printing roller S₆. In a similar way the information from the apparatus TE consists of negative voltage impulses (FIG. 14b) which are produced every time the signals I_c, II_c, III_c, etc. are sensed by the photoelectric cell (FIG. 3). Such voltage impulses indicate the position on the paper of the monochromatic images printed by rollers S₁, S₂, S₃ etc.

FIG. 14b shows 3 signals corresponding to the sensing of the signals I_c, II_c, III_c by the cell E of detector TE, while FIG. 14a shows three corresponding signals generated by TM. If the corresponding signals from TE and TM occur simultaneously the monochromatic images printed by rollers S₁, S₂, S₃, etc. are in the correct position with respect to the roller S₆ and the image printed by the latter, and therefore the apparatus is in register; otherwise there is an error of register.

In FIG. 14, it has been assumed that there was no error of register in the case of the first signals, an error of register in a certain sense in the case of the second signals, and an error of register in the opposite sense in the case of the third signals.

In FIG. 14, the abscissae represent time, and therefore the difference of phase between the second signal is the error of register measured in terms of time. Of course, it is important to know the error of register measured in terms of position and for this purpose the speed of displacement of the paper must be considered.

FIGS. 14c and 14d represent the output voltages from the squaring circuits 43 (points 109 and 110); when their input terminals (points 46 and 47) receive the impulse shown on FIGS. 14a and 14b.

FIGS. 14e and 14f show the voltages at the points 102 and 101 of one of the bistable circuits and FIGS. 14g and 14h show the voltages at the points 104 and 103 of the other bistable circuit.

FIGS. 14i and 14l show the grid voltages at points 111 and 112 of the integrator circuits. It is clearly seen that one of the integrators has a negative grid voltage when the error of register is in one sense, and that such negative grid voltage persists for a length of time equal to the error of register in time, while the second integrator has a negative grid voltage, when the error of register is in the opposite sense, and which persists a time which is equal to the error of register measured as time.

The points 113 of the integrator circuits are supplied with a voltage proportional to the speed of the paper.

The integrators produce voltages at their output termi-

nals 48, 49, as represented by FIGS. 14m and 14n, only when their grid voltages are negative.

The value of the voltage DVi (FIG. 14m or 14n) is proportional to the product of the time during which the grid of each integrator is negative (error of register in time) multiplied by the voltage at point 113 (proportional to the paper speed); therefore the voltage DVi is proportional to the error of register in printing.

Besides, one or the other integrator presents the voltage, thereby indicating the sense of the error.

(d) *Driving Device of the Correcting Circuit*

In accordance the present invention the outlet terminal 48 or 49 of the integrator of each channel of the control device C, is connected to the inlet 18 of the circuit represented on FIG. 8, which is formed substantially by thyratrons 19, 20, 21 etc., the number of which is equal to the number of the printing sections S_1, S_2, S_3 etc., excepting the last one, indicated at S_6 .

The action of each of the thyratrons causes the excitation of a corresponding relay Ra_1, Ra_2, Ra_3 , etc., that feeds energizing current to the corresponding correction motor M_1, M_2, M_3 etc. (FIG. 3) to effect rotation of the latter in one direction.

A similar circuit is provided for the integrator of the other channel and drives the same correction motors, but in the opposite direction.

The correction signals coming from circuit C are directed to the various machine sections under the control of the screen grids of tubes 19, 20, 21 etc.

When the voltage at the outlet of the integrator of a channel exceeds the value of the negative control grid bias of the various tubes 19, 20, 21 etc. (and this happens when the error in the register exceeds a certain fixed value), the screen grid of the related tube is given a zero potential and starts to conduct, while the other tubes, the screen grids of which are at negative potential, are blocked.

When a tube begins to conduct and the corresponding relay is energized, for instance relay Ra_1 , a delay circuit (not shown) is activated, and keeps the relay excited and consequently maintains the correction current for a fixed time.

(e) *Selector Device S*

The selector device is formed by a squaring circuit, FIG. 9 and by the selector circuit itself (FIG. 11).

The inlet 22 of the circuit (FIG. 9) receives the signal coming from point 10 of the circuit of FIG. 4.

The operation of the circuit of FIG. 9 will be apparent from the curves of FIG. 10 giving the variations of the voltage at several points of the circuit in relation to time. Specifically, curve 28 gives the voltage at the inlet 22, curve 29 represents the voltage at point 25, curve 30 represents the voltage at point 26, and curve 31 represents the voltage at the outlet 27. The various curves have a periodical pattern and the portions of the curves indicated at A and B correspond to the passage of a register mark I_c, II_c etc. printed on the sheet.

The function of the circuit of FIG. 9 is to give a positive impulse at the outlet 27 for each mark printed on the paper.

The selector illustrated by FIG. 11 consists of a number of bistable circuits connected together by the known ring connection. In the drawing, three sections are shown and are schematically divided by lines F—F, G—G.

The inlet 32 is connected to point 27 of FIG. 9.

The shape of the voltage curves are shown on FIG. 12.

Curve 33 shows the voltage of the arriving signal, the line 34 on the left is the inlet front, the line 35 on the right, is the outlet front.

Curve 36 shows the shape of voltages entering the selector, curves 37, 38, 39 show the polarization voltages of the screen grids of tubes 19, 20, 21, (FIG. 8). Point 40, that is the first section (FIG. 11) feeds the 75

screen grids of tubes 19 (in both channels), point 41, that is located in the corresponding position, but in the second section of FIG. 11, feeds the screen grids of tubes 20 and so on.

The result is that the possible integration of the integrator that can be caused by the inlet front of the first marks I_c (in the case when there is an error in the register) causes the interference operation only of tube 19 of FIG. 8, which is the only one that, in that interval of time, has its screen grid grounded.

If, on the contrary, the integration is caused by the inlet front of the second signal II_c , tube 20 (FIG. 8) will enter into operation, as that tube has its screen grid grounded during that interval of time.

It is to be understood that the above described arrangements are illustrative and that numerous variations and modifications can be effected therein without departing from the scope or spirit of this invention.

Particularly, the selector, schematically shown on FIG. 2, can be of electronic construction—as described—or of a mechanical or electro-mechanical type.

Furthermore the method can be practiced with the following variation described with reference to FIG. 13.

The first section of the machine prints on the edge of the sheet as many marks IA, IB, IC, ID, IE as there are subsequent sections. Each following section prints a register mark, shown as II, III, IV, V, VI.

The printing rolls are built in such a way as to have, when the monochromatic images are perfectly registered, the corresponding marks aligned with each other, that is, mark II facing mark IA, mark III corresponding to mark IB, etc. as on FIG. 13. After passing through the last printing section, the paired marks are sensed by a photoelectric cell device generating signals which act on inlets 46 and 47 (FIG. 6) to produce control signals at outlets 48 and 49 as previously described herein.

I claim:

1. A method for controlling register of the successive monochromatic images applied to each part of a web of paper by a series of printing couples in a rotogravure printing press, comprising the steps of

A. applying to each part of the web, at each of the series of printing couples other than one of the latter, a characteristically located register mark in addition to the corresponding monochromatic image,

B. successively detecting, only at the last printing couple of said series, the several register marks applied previously to each part of the web,

C. comparing the timing of the successively detected register marks with the timing of reference signals generated so as to correspond to the positional relationship between each part of the web and the point at which the register marks are detected,

D. generating successive correction signals in response to any deviations between said detected register marks and reference signals,

E. supplying the successive correction signals to the several printing couples, in order, with the exception of said one printing couple, and

F. positionally adjusting each printing couple to which a correction signal is supplied in the sense to eliminate the deviation between the related register mark and reference signal, thereby to maintain correct register between the monochromatic image applied at said one printing couple and the monochromatic images applied at the other printing couples.

2. The method as in claim 1; wherein said one printing couple is the last of said series of printing couples, and said reference signals are generated in response to the rotation of said last printing couple.

3. The method as in claim 1; wherein said one printing couple is the first of said series printing couples, and wherein characteristically located reference marks cor-

- responding in number to said other printing couples are applied to each part of the web at said first printing couple, and said reference marks are detected at said last printing couple to establish the timing of said reference signals.
4. In a multicolor printing press having a series of printing cylinders acting successively on a web of paper to apply related superposed monochromatic images to each section of the web, apparatus for controlling register of the monochromatic images applied to each section of the web, comprising:
- A. means on each of the printing cylinders, with the exception of one of said cylinders, for applying to each section of the web a characteristically located register mark in addition to the corresponding monochromatic image;
  - B. drive means for simultaneously rotating said printing cylinders and including correction means for rotationally adjusting each of the printing cylinders except said one cylinder;
  - C. photoelectric detecting means at the last of said printing cylinders successively sensing the register marks applied to each section of the web and generating successive, correspondingly timed electrical register signals;
  - D. means generating reference signals timed so as to correspond to the timing of said register signals upon correct register of the corresponding images with the image applied by said one cylinder;
  - E. a device comparing said register signals with said reference signals and generating a correction signal in response to any deviation of a register signal from the corresponding reference signal; and
  - F. selector means connecting said device successively with each of said correction means associated with the printing cylinders except said one cylinder so that each correction signal is thereby fed to the related correction means for rotationally adjusting the corresponding printing cylinder in the sense eliminating the register error leading to the generation of said correction signal.
5. In a multicolor printing press, apparatus for controlling register of the monochromatic images applied to each section of the web as in claim 4;
- wherein said one cylinder is the last printing cylinder of said series, and
- said means generating reference signals includes electro-magnetic means driven with said last cylinder so that the timing of said reference signals is proportional to the rotational speed of said last cylinder.
6. In a multicolor printing press, apparatus for controlling register of the monochromatic images applied to each section of the web as in claim 4;
- wherein said one cylinder is the first printing cylinder of said series, and
- said means generating reference signals includes
- a. means on said first cylinder applying to each section of the web a series of reference marks characteristically located so as to have predetermined positional relationships with respect to the register marks applied to that section of the web by the following printing cylinders upon correct register of the images applied by said following cylinders with the image applied by said first cylinder, and
  - b. additional photoelectric detecting means at said last printing cylinder successively sensing the reference marks applied to each section of the web by the first cylinder and generating said reference signals at the frequency with which said reference marks pass said additional photoelectric detecting means.
7. In a multicolor printing press, apparatus for controlling register of the monochromatic images applied to each section of the web as in claim 4;

5
8
wherein said means generating reference signals includes

- a. a magnetic drum rotatable with said one printing cylinder and having magnetic impulses spaced apart circumferentially thereon,
  - b. a pick-up head located adjacent said drum to provide electrical impulses at the frequency at which said magnetic impulses pass said head,
  - c. amplifier means receiving said electrical impulses from said head and amplifying the same to provide said reference signals, and
  - d. means controlling the amplification by said amplifier in accordance with the speed of said drive means so that the amplitude of said reference signals is independent of the speed of rotation of said one cylinder.
8. In a multicolor printing press, apparatus for controlling register of the monochromatic images applied to each section of the web as in claim 4;
- 20
wherein said device comparing the register signals with the reference signals includes electronic circuit means having two channels receiving said register and reference signals and each being made up of a squaring circuit, a bi-stable circuit and an integrator circuit, said circuits of each channel being interconnected to provide a voltage impulse at the output of the integrator circuit of one of said channels when a register signal precedes the corresponding reference signal and to provide a voltage impulse at the output of the integrator circuit of the other channel when a register signal lags with respect to the corresponding reference signal.
- 25
9. In a multicolor printing press, apparatus for controlling register of the monochromatic images applied to each section of the web as in claim 8;
- 30
further comprising means supplying a voltage proportional to the speed of said drive means to said integrator circuit of each channel of said device comparing the register signals with the reference signals and causing said voltage impulses at the output of each integrator circuit to have a magnitude proportional to both the deviation, in point of time, between the register and reference signals being compared, and the speed of movement of the web so that said magnitude of the voltage impulse is proportional to the extent of the register error.
- 35
10. In a multicolor printing press, apparatus for controlling register of the monochromatic images applied to each section of the web as in claim 8;
- 40
50
wherein said device further includes
- a. two thyratron circuits connected to the respective outputs of the integrator circuits of said channels, each of said thyratron circuits having a series of thyratrons corresponding to the printing cylinders other than said one cylinder and being normally blocked, and
  - b. a relay connected with each thyratron to be energized by a voltage impulse from the related channel only when the thyratron is in conductive condition; and
- 55
wherein said selector means includes
- a. electronic means for successively rendering conductive the thyratrons of each thyratron circuit, and
  - b. circuit means controlled by each of said relays and extending to the related correction means for operating the latter only when a voltage impulse is received from one of said channels at a time when the related thyratron is rendered conductive.
- 60
65
70
75
11. In a multicolor printing press, apparatus for controlling register of the monochromatic images applied to each section of the web as in claim 10;
- wherein each thyratron has a screen grid normally

maintained at a negative potential, and said electronic means of the selector means successively grounds the screen grids of the thyratrons.

12. In a multicolor printing press, apparatus for controlling register of the monochromatic images applied to each section of the web as in claim 10; further comprising time delay means for each relay operative to maintain the latter in energized condi-

tion for a predetermined time following energization thereof through the related thyratron.
